MOLD

John T. Brubaker, Wilkinsburg, Pa.

Application July 7, 1933, Serial No. 679,395

5 Claims. (Cl. 107—19)

My invention relates to molds for food materials and particularly to devices for molding food products, such as lamb patties, croquettes or the like.

5 In forming lamb patties, for example, it has been necessary to shape them by hand and the process is rather laborious and considerable time is required for the formation of each article. When patties are formed in this manner it is 10 difficult to make them of uniform shape and size. It is undesirable also that the food be in contact with the hands of the persons making the patties.

I provide a molding device by means of which lamb patties or similar articles of food may be 15 prepared without contact with the hands of the operator and with substantial saving in time. In addition, the completed articles are of uniform size and shape and accordingly they are more attractive in appearance.

20 The molding device consists in general of a molding chamber that is adjustable to provide for different sizes of molded articles and it comprises also an arrangement whereby, after the material is molded, a strip or band of bacon may be placed around the molded portion of the patty and secured in position thereon. The patty may then be withdrawn from the mold in its completed form.

25 The details of my invention will be described 30 in connection with the accompanying drawing, in which Fig. 1 is a view in longitudinal section of a molding device; Fig. 2 is a side elevational view of the molding device of Fig. 1; Fig. 3 is an end elevation as viewed from the left Fig. 2, the cover being removed; Fig. 4 is an end elevation of a molding attachment for the device of Fig. 1; Fig. 5 is a view in longitudinal section taken on line V—V of Fig. 4; Figs. 6 and 7 are 35 respectively reduced side and end elevational views of a stuffing device for attachment to the molding device of Fig. 1; Fig. 8 is a reduced 40 perspective view of a decorating device that is adapted to be attached to the stuffing device of Figs. 6 and 7.

45 Referring particularly to Figs. 1, 2 and 3, the molding device of my invention comprises a hollow cylinder 1 which may be of sheet-metal and is open at both ends thereof. A plunger 2 which may also be of sheet-metal and is closed at both 50 ends thereof telescopes within the hollow cylinder 1 and it is slidably movable therein for the purpose of adjusting the length of a molding chamber 3 at the left as viewed in Figs. 1 and 2.

55 Adjacent the left or upper end of the hollow cylinder 1, as the device is used in practice, a

sleeve 4 surrounds the cylinder 1 and is slidably movable relative thereto. The sleeve 4, which is in the form of an annular band, carries two semi-cylindrical members 5 that are connected thereto by means of hinges 6, the latter appearing in Fig. 2. The members 5 are provided on their interior surfaces with a series of grooves 7 for a purpose to be later described.

A flanged cover plate 8 is adapted to fit over the ends of the hinged members 5 when the latter are in their closed positions in which they are illustrated in Figs. 1 and 2. The plunger 2 is provided at its lower end with a spring latch member 10 by means of which it is adapted to be detachably secured to the cylinder 1 by means 15 of a hollow or tubular member 11 having a series of notches or slots 12 therein for engagement by a hook 13 at the upper end of the member 10. The hook 13 is also adapted to engage an inwardly flanged member 14 that is secured to the sleeve 4 for the purpose of detachably connecting the plunger 2 and the sleeve 4 for permitting movement of the cylinder 1 without disturbing the relative positions of the plunger 2 and the sleeve 4.

20 The cylinder 1 is provided with an outwardly extending member 15 by means of which the cylinder 1 may be moved with respect to the sleeve 4 and also with respect to the plunger 2 when the latter is connected to the sleeve 4. It 25 will be understood that when the latch member 10 connects the plunger 2 to the cylinder 1 both of these parts may be moved together relative to the sleeve 4.

25 In the operation of the molding device, it may be assumed that the material to be molded for the forming of lamb patties has been prepared in suitable form for molding. The plunger 2 is adjusted with respect to the cylinder 1 to provide a molding chamber 3 of desired depth in the open end of the cylinder 1. The latch member 10 engages one of the slots 12 to retain the plunger in its adjusted position. The cover 8 is removed and the hinged members 5 are opened by swinging them outwardly beyond the dot-and-dash lines of Fig. 2. The cylinder 1, together with the plunger 2, is then withdrawn downwardly through the sleeve 4 until the top of the cylinder 1 is substantially flush with the top of the sleeve 4. The material for the molded portion of the lamb patty is then inserted in the chamber provided by the open end of the cylinder 1 until the space is substantially filled.

30 The cylinder 1, together with the plunger 2, is then moved upwardly through the sleeve 3 to 35

substantially the position shown in Figs. 1 and 2. A strip or a band of bacon is placed around the upper end of the cylinder 1 with the molded material inside thereof and the hinged members 5 are closed, the grooves 7 operating to retain the bacon in position. The cover 8 may then be placed on the outer ends of the members 5 and the plunger 2 is moved upwardly to cause the material within the cylinder to be pressed or compacted within the upper end of the cylinder 1.

The latch member 19 is then released and the cylinder 1 is withdrawn downwardly without disturbing the relative positions of the sleeve 4 and the plunger 2. The molded material remains in its position on top of the plunger 2. The strip or band of bacon is then secured to the central portion of the molded material of the lamb patty, as by means of small wooden pins which may be of any suitable size or shape. This latter operation is permitted by slots 17 in the hinged members 5. The slots may be of such size and shape as to readily permit the openings of the members 5 after the pins are in position. Slots may be also provided in the end of the cylinder 1, but if the device is manipulated in the manner described herein, they are unnecessary.

When the cover 8 has been removed, the hinged members 5 are opened outwardly beyond the positions shown by dot-and-dash lines, Fig. 2, the plunger 2 is moved upwardly relative to the cylinder 1 and sleeve 4 to raise the molded portion of the lamb patty on a level with the tops of the cylinder 1 and sleeve 4, whereby the completed patty may be removed. The apparatus is then adjusted for a succeeding lamb patty and the operation described above is repeated.

The foregoing description of the operation of the molding device has been given by way of example as it is obvious that the sequence of manipulation of the parts may be varied somewhat without affecting the results secured thereby.

It will be noted from the foregoing that my improved molding device is simple in construction and expeditious in operation to form lamb patties of desired size and the product is of uniform size and appearance, inasmuch as all of the material for forming the patties may be handled by suitable implements without touching the hands.

While the principal purpose for which the molding device is provided is as described above, it is also adapted for other uses such, for example, as in molding croquettes or ice cream in novel forms by means of the apparatus shown in Figs. 4 and 5. A molding device 19, having an annular sleeve 29 for surrounding the upper end of the hollow cylinder 1 is connected to the interior of the cylinder 1 by means of a relatively small aperture 21 whereby material may be forced therethrough by means of the operation of the plunger 2. It will be understood that the outer end of the mold 19 may be held against a vessel or flat surface and the molded article may be readily separated from the remainder of the material by reason of the relatively small aperture 21 which connects it thereto. While the molding device 19 is shown of substantially pyramidal form it may have various shapes as desired.

A further adaptation of the device is in connection with the device shown in Figs. 6 and 7 which comprises a tubular member 23 adapted to fit over

the upper end of the cylinder 1 and to be fastened thereto as by means of a bayonet joint 24 and which is provided with a nozzle 25 of substantially rectangular form which may be used, for example, in preparing stuffed pork chops. This operation, which has been performed manually heretofore, has always been attended with difficulties. However, by means of the device of Figs. 1 and 2, when provided with the attachment shown in Figs. 6 and 7, the stuffing material may be easily and readily forced into suitable slits or openings provided therefor in the pork chops by inserting the nozzle therein and operating the plunger 2 to force the material through the nozzle 25.

A further adaptation of the molding device is provided by the use of the decorating device 26 shown in Fig. 8. This device, which is of such cross-section and size as to fit upon the nozzle 25, is provided with a series of spaced openings or holes 27 by means of which decorating material may be supplied to cakes or other articles of food, such, for example, as in providing them with chocolate or other plastic decorating material.

The foregoing uses for which my improved molding device is adapted are given by way of example only and it is not intended to be limited thereto except as expressed in the claims.

I claim:

1. In combination, a hollow cylinder, a sleeve surrounding said cylinder and slidably relative thereto, a movable plunger in said cylinder, and means for detachably securing said plunger to said sleeve and permitting movement of said cylinder relative to said sleeve and said plunger.

2. In combination, a hollow cylinder, a sleeve surrounding said cylinder and slidably relative thereto, a movable plunger in said cylinder, and means for detachably securing said plunger to said sleeve and which is adapted to permit movement of said cylinder relative to said sleeve and said plunger, the securing means comprising a latch mechanism connected to said plunger and extending exteriorly of said cylinder for engagement with said sleeve.

3. A mold for food materials comprising a tubular member having an open end, a sleeve around said tubular member and slidably movable relatively thereto, a movable plunger in said tubular member for regulating the length of the chamber provided thereby, and hinged members carried by said sleeve for enclosing said tubular member adjacent its open end to provide an annular chamber for a strip or band of material around the molded material.

4. In combination, a hollow cylinder, a plunger movable therein to provide a chamber of variable capacity for receiving material and said plunger being movable also to eject said material from said cylinder, a sleeve surrounding said cylinder, means for connecting the sleeve to said plunger, and movable means hinged on said sleeve for enclosing said cylinder to provide an annular space therearound.

5. In combination, a hollow member for providing a molding chamber for food material, a plunger movable in said chamber for varying the length of said chamber and for ejecting molded material therefrom, means having members thereon for providing an annular chamber around the molded material whereby a band or strip of other material may be placed around the molded material, and means for latching said first-mentioned means to said plunger.
